UNITED STATES PATENT OFFICE.

WILLIAM A. BURGER, OF BERKELEY, CALIFORNIA, ASSIGNOR OF ONE-HALF TO HANS P. HENNINGSEN, OF OAKLAND, CALIFORNIA.

FOLDING BED.

Application filed July 20, 1925. Serial No. 44,652.

My invention relates in general to beds of the folding type, and has particular reference to a so called wall bed. This title is intended to include attaching or mounting accommodations such as cabinets, closets and other convenient locations including an ordinary vertical wall of a room.

The salient features and objects of my invention reside in a bed structure embodying a combination of parts, so assembled as to offer a simple, cheap and practical folding bed, especially adapted for use in dwellings and the like where space is at a premium, and where it is desirable to provide a disappearing bed which can be quickly and conveniently set up or hidden away as occasion demands.

The preferred form of the invention is shown on the accompanying drawings and in which:

Figure 1 is a plan of the bed, minus the mattress set up for use, with the cabinet therefor shown in horizontal section.

Fig. 2 is a view in side elevation of the bed as set up and showing the cabinet in vertical section with the doors removed.

Fig. 3 is a view in longitudinal vertical section showing the bed about to be folded into the cabinet.

Fig. 4 is a view similar to Fig. 3 and showing the bed folded within the cabinet.

Fig. 5 is a view in front elevation of the cabinet and showing the bed in dotted lines folded therein.

Fig. 6 is a longitudinal section, on an enlarged scale, of the hinged structure for folding the bed; and Fig. 7 is a similar view of the structure about to be folded; and Fig. 8 is a like view showing the structure as when folded; and

Fig. 9 is an enlarged detail view of the adjustable connections for the draw springs for the bed.

Referring now to the drawings and the figures thereof in detail: The letter A represents a cabinet or it may just as well be a closet or the like; in fact my bed may be set up against any wall even in the absence of side pieces, as the mounting parts are designed particularly so as to make the bed applicable to a single vertical supporting or mounting surface. This latter feature is an object of the invention and of prime importance.

First of all the bed will include a pair of connected arms 5 and 6 pivotally mounted to a pair of housings 7 and 7' attached to the back wall of the cabinet. These housings are made to confine the rollers 8 on the ends of the arms so as to permit the arm ends to vertically change their positions when the bed is folded or extended. Suitable restraining links 9 are pivoted to the base of the housing mounting and to the arms, to guide and hold the arms in alignment.

Connected to each of the arms 5 and 6 intermediate their ends is a strong coil spring 10, the purpose of which is to draw the bed into the cabinet during the folding action. The wall mountings for these springs are made adjustable as best shown in Fig. 9. The same comprises a threaded screw eye 11 engaging a plate or the like 12, which in turn is made with an eye 13 to hook over the hookplate 14. A nut 15 for the end of the screw eye 11 holds the same in the plate, and when the springs 10 become weak from use, the same may be strengthened by screwing down on the nut 15.

The bed structure per se is made with side bars 16 and 17, two sections for each side of the bed. The usual head and foot parts 18 and 19 respectively are carried by the bars. The head is rigid and the foot is also rigidly fixed, but the feet 20 are pivoted as at 21 to the ends of the side bar sections 17. The side bar sections on both sides of the bed are pivotally connected to a relatively large plate 22, the latter having legs 23 with floor rollers 24. The pivot points for the side bar sections are positioned as at 25, so as to leave the extremities 26 of the bars free to pivotally connect with links 27 and 28 as at 29. The link 28 is shorter than the link 27 and the same is connected by a pivot 30 to a guide link 31, which latter is pivoted at its end 32 to the plate 22. Connecting at the pivot point 30 is a relatively long link 33, which has its end pivotally attached as at 34 to crank piece 35. This crank is connected by the pivot 36 to the end of the link 27.

Anchored by the adjustable connection 37 is a coil spring 38 having its opposite end attached to the crank piece 35 at the pivot 34. Instead of extending the side bar sections beyond the pivots 25, strips or the like 39 may be secured to the sections to extend them beyond the pivots to connect with the

links 27 and 28 respectively. In this event the pivots 25 will be positioned at the extremities of the bars as shown.

Referring to Fig. 6 it will be noted that 5 the link 27 with the extremity 26 of its pivotally connected foot section of the bed, form a toggle-joint. The line of action of any force applied through the crank 35; as for instance by the springs 10 or 38; is in 10 line with the pivot points 36, 29 and 25 at the right of the figure, and thereby serves only to increase pivot friction and resist closing of the bed, so that, while a slight lift on the foot section 17 against this resistance 15 will "break" the toggle and allow the bed to close, no amount of force applied to the head section 16 will initiate folding of the bed. For purposes of mechanical expediency, the toggle-joint 27, 29, 26, is permitted to buckle 20 very slightly beyond fully extended position; a flange on top of the large plate 22 of the base frame member, serving to hold the toggle-joint cocked against collapse in this reverse direction.

25 The bar sections 17 or rather the foot section of the bed control the folding action of the bed through the means of the crank 35. As long as the bed is extended, the head section will not fold until a lift is imparted to 30 the foot section. When the foot section is lifted, the crank piece 35 is caused to rotate past its vertical centerline and the spring 38 pulls the crank during this movement, which in turn causes the link 33 to turn the link 31, 35 and which latter causes link 28 to move and break the hinge made by the pivot 29, and thus the head section of the bed begins to fold or rather raise up. As this occurs the bed as a whole is released to the influence 40 of the springs 10, and the pull imparted thereby upon the bed draws the bed into the cabinet and at the same time completes the folding action.

45 The two springs 10 and the two springs 38 do the work, first assisted by the manual lifting of the foot section through a predetermined angle. The springs 38 fold the sections and the springs 10 pull them into the cabinet.

50 To fold the legs 20 in folding position, as well as hold the same rigid when in extended position, supplemental bars 40 are provided and pivoted to the plate 22 at one end and to the legs 20 at the other end below 55 the pivots 21.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to 60 have it understood that the device shown is

merely illustrative and that such changes may be made, when desired, as fall within the scope of the appended claims.

Having thus described my invention, what I claim as new and desire to secure by Letters Patent of the United States is the following:

1. A folding bed comprising a support, a head section and a foot section pivoted to said support for foldable movement from 75 horizontal to vertical, a toggle link connected to said foot section and to said support whereby the foot section constitutes one leg of a toggle joint, linkage connecting said head section to the toggle joint for folding movement with the foot section; said linkage being locked by the toggle joint when the foot section is horizontal; and spring means tending to fold said head section, whereby the bed will be folded by said as spring only after folding motion of the foot section has been manually initiated to break the toggle.

2. In a folding bed, a support, a head section and a foot section pivoted to said support for movement from extended horizontal position to folded vertical position, a toggle joint adapted to be broken by movement of said foot section from horizontal position; said toggle joint comprising pivoted links 80 connecting said sections, and being operative when extended to lock said head section in extended position; and spring means for urging said links to hold the sections extended while the toggle is locked and for collapsing said toggle to fold the sections when the toggle has been broken.

3. A folding bed comprising a base frame, a head section and a foot section pivoted thereto and each provided with an extension 105 beyond its pivoting point, a crank pivoted between its ends to said frame, a toggle-joint connecting one end of said crank to the extension of the foot section, pivoted means operatively connecting the other end of said crank to the extension of the head section, a spring connected to the crank and toggle linkage tending to collapse said toggle in other than dead-center position of the toggle, and cocking means for preventing collapse 110 of said toggle in one direction only; said parts being proportioned and positioned to retain said toggle slightly beyond dead center position when the bed is unfolded whereby the cocking means retains the toggle 115 cocked and said spring resists breaking of the toggle.

4. A folding bed comprising a base frame, a head section and a foot section pivoted thereto and each provided with an extension 125 beyond its pivoting point, a crank pivoted between its ends to said frame, a toggle-joint connecting one end of said crank to the extension of the foot section, pivoted means operatively connecting the other end 130

of said crank to the extension of the head section, a spring connected to the crank and toggle linkage tending to collapse said toggle in other than dead-center position of the toggle, and cocking means for preventing collapse of said toggle in one direction only; a supporting structure in confronting relation with said head section, and means connecting said head section with said supporting structure and including a spring tending to pull the head section toward the structure; the parts being proportioned and positioned as described whereby the toggle joint is cocked when the bed is unfolded to horizontal position to prevent retraction of said springs and may be uncocked by manually lifting said foot section. 15

In testimony whereof I affix my signature.

WILLIAM A. BURGER.
